CHAIR

Walter C. Lucas, Asheboro, N. C.

Application April 13, 1950, Serial No. 9,184

Term of patent 7 years

(Cl. D15—8)

To all whom it may concern:

Be it known that I, Walter C. Lucas, a citizen of the United States, residing at Asheboro, county of Randolph, State of North Carolina, have invented a new, original, and ornamental Design for Chair, of which the following is a specification, reference being had to the accompanying drawings, forming a part thereof, wherein:

Figure 1 is a rear perspective view of a chair showing my new design, and

Figure 2 is a front perspective view of the chair.

The chair is particularly characterized by the rear legs extending within the seat frame and through the rear corners of the seat to support the backrest.

I claim:

The ornamental design for a chair, substantially as shown and described.

WALTER C. LUCAS.
